(57) **CLAIM**

The ornamental design for a pet product packaging as shown and described.

DESCRIPTION

FIG. 1 is a front and right-side perspective view of an exemplary pet product packaging showing the new design. FIG. 2 is a rear and left-side perspective view thereof.

FIG. 3 is a front perspective view thereof.

FIG. 4 is a front elevation view thereof.

FIG. 5 is a rear elevation view thereof.

FIG. 6 is a top plan view thereof.

FIG. 7 is a bottom perspective thereof.

FIG. 8 is a right-side elevation view thereof; and,

FIG. 9 is a left-side elevation view thereof.

The broken lines depict portions of the pet product packaging that form no part of the claimed design.

The cat imagery, “World’s Smartest Cat Litter,” and “PRETTYLITTER,” forming part of the claimed design, are registered trademarks of Pretty Litter, Inc. “Health Monitoring Cat Litter,” forming part of the claimed design, is the subject of a trademark application of Pretty Litter, Inc.

1 Claim, 9 Drawing Sheets
